Patented Mar. 16, 1915.

UNITED STATES PATENT OFFICE.

ISAAC HOLZMARK, OF ST. LOUIS, MISSOURI.

SHOEMAKER'S JACK.

1,131,837.

Specification of Letters Patent. Patented Mar. 16, 1915.

Application filed April 24, 1913. Serial No. 763,439.

To all whom it may concern:

Be it known that I, ISAAC HOLZMARK, a citizen of the United States, and resident of St. Louis, Missouri, have invented certain new and useful Improvements in Shoemakers' Jacks, of which the following is a specification containing a full, clear, and exact description, reference being had to the accompanying drawings, forming a part 10 hereof.

My invention relates to improvements in shoemakers' jacks, and the object of my invention is to construct a jack comprising a floor stand arranged to be fixedly secured in 15 place and having at its upper end an upwardly open vertical socket, and opposite horizontally-alining sockets all arranged to interchangeably receive the stem of the last in such manner that the said stem may be 20 rotated in any one of said sockets, and the last may be held in any desired position.

With the above purposes in view my invention consists in certain novel features of construction and arrangement of parts as 25 will be hereinafter more fully described, pointed out in the claim and illustrated by the accompanying drawing, in which—

Figure 1 is an elevation of my improved jack showing certain of the parts in section; 30 Fig. 2 is an elevation of the upper portion of the jack taken at right angles to Fig. 1; and Fig. 3 is a sectional plan taken on the line 3—3 of Fig. 2.

Referring by numerals to the accompanying drawing: 5 designates the standard having an integral base 6 which is arranged to be secured to a suitable support.

The standard is preferably formed hollow throughout its length and has at its top a 40 vertically disposed socket 7 and two horizontally alining openings 8 forming sockets, all of said sockets being each of like diameter throughout its length and preferably circular.

45 9 designates the last-shank, the body portion of which is preferably cylindrical to form a cylindrical journal 10 arranged to fit interchangeably throughout its length in any of said sockets, and at its upper end the

shank is reduced in order to fit the socket 50 of the last 11, which is of ordinary construction. In order to limit the insertion of the journal 10 into said sockets there is formed around the body of the shank 9 a collar 12.

55 Formed integral with the shank there are the diametrically opposed stubs 13 which are arranged to secure the free ends of an elastic coiled spring which is of sufficient length to extend continuously from one of 60 said stubs to the other, and act as a last-strap 14.

Formed in the wall of the standard at right angles to the alining openings 8 there is a tapped hole 15 arranged to receive a set 65 screw 16 which provides means for securing the last-shank against rotation.

It is to be observed that the jack is constructed of a number of parts, all of which may be readily formed by casting, that the 70 arrangement of sockets in the top of the standard permits of adjustment of the last-shank reversibly and interchangeably from one socket to the other, and that the circular sockets and cylindrical journal of 75 the last-shank provide means whereby the last and its shank may be rotated for an additional range of adjustment, so that all necessary positions of "work" may be had.

If desired, the set screw supplies means 80 whereby the last may be locked in any selected position.

By the construction shown and described all "working" parts of a jack are dispensed with, which not only decreases the cost of 85 producing the jack but also increases the life in that there are no parts which may be readily broken.

I claim:

The improved shoemaker's jack, comprising 90 a long floor-standard having at its upper end three (3) separate sockets each of like diameter throughout its length; two of said sockets extending horizontally and opening on opposite sides of said standard, 95 and the third socket extending vertically and opening on the top of said standard and extending at a right-angle to the horizontal

2
sockets; and a last-shank having a journal which is cylindrical throughout its length and arranged to interchangeably fit within each of said three sockets; whereby said 5 last-shank may project from opposite sides and top of said standard during use.

In testimony whereof, I have signed my
